UNITED STATES PATENT OFFICE

134,331

DESIGN FOR A REFRIGERATOR

Leonard H. Darbyshire, Detroit, Mich., assignor
to Borg-Warner Corporation, Chicago, Ill., a
corporation of Illinois

Application April 17, 1941, Serial No. 100,469

Term of patent 14 years

To all whom it may concern:

Be it known that I, Leonard H. Darbyshire, a citizen of the United States and resident of the city of Detroit, in the county of Wayne and State of Michigan, have invented a new, original, and ornamental Design for a Refrigerator, of which the following is a specification, reference being had to the accompanying drawing, forming a part thereof, wherein:

Fig. 1 is a front perspective view of a refrigerator, showing my design, with the door in open position;

Fig. 2 is an enlarged fragmentary cross-sec-

tional view as it would appear taken at a point indicated by the line 2—2 on Fig. 1 but with the door in closed position; and

Fig. 3 is a top plan view of the refrigerator, on a reduced scale, with the door in closed position.

The present design is characterized by the rounded throat trim of the door frame portion of the refrigerator casing.

I claim:

The ornamental design for a refrigerator, substantially as shown and described.

LEONARD H. DARBYSHIRE.
